(57) **CLAIM**

The ornamental design for a ring, as shown and described.

DESCRIPTION

FIG. 1 is a front perspective view of a ring, showing our new design;

FIG. 2 is a front view of the design illustrated in FIG. 1;
FIG. 3 is a rear view of the design illustrated in FIG. 1;
FIG. 4 is a right side view of the design illustrated in FIG. 1;

FIG. 5 is a left side view of the design illustrated in FIG. 1;
FIG. 6 is a top view of the design illustrated in FIG. 1; and,
FIG. 7 is a bottom view of the design illustrated in FIG. 1.
The broken lines in the drawings represent portions of the
ring and form no part of the claimed design.
